UNITED STATES PATENT OFFICE.

GEORGE F. COOPER, OF DETROIT, MICHIGAN.

DISPLAY-RACK.

1,351,994.

Specification of Letters Patent.

Patented Sept. 7, 1920.

Application filed February 13, 1918. Serial No. 216,982.

To all whom it may concern:

Be it known that I, GEORGE F. COOPER, a citizen of the United States of America, residing at Detroit, in the county of Wayne 5 and State of Michigan, have invented certain new and useful Improvements in Display-Racks, of which the following is a specification, reference being had therein to the accompanying drawings.

- 10 In the use of display cases for clothing and more particularly for men's and boys' coats and vests, various devices have been employed wherein a standard carrying two rows of coat forms or hangers can be withdrawn from an inclosing cabinet for inspection, and revolved so that either row of coat forms may be brought to the front, but as these rows of forms are disposed side by side, it has been impracticable up to the 15 present time, to dust off and clean the inner portions or adjacent sides of the two rows of garments, except by removing the hangers one by one, a laborious and tedious process.
- 20 This invention relates to a floor cabinet rack for men's and boys' clothing, whereby the rack carrying the garments upon their hangers, may be moved out of the cabinet and swung instantly into such a position 25 that all parts of the garments are accessible for cleaning, dusting and rearrangement without removing the hangers from the rack.

The invention consists in the matters 30 hereinafter set forth, and more particularly pointed out in the appended claim.

In the drawings,

Figure 1 is a plan view, with a cabinet shown in section, of a device that embodies 35 features of the invention;

Fig. 2 is a view of the same in side elevation, with the cabinet partially in section;

Fig. 3 is an end view of the same with the cabinet partially in transverse section;

40 Fig. 4 is a view similar to Fig. 1, drawn to a reduced scale, showing the device swung out of its cabinet for complete inspection of the contents; and

Fig. 5 is an enlarged detail of one form of 45 latch for securing the parts of hanger rods together.

As herein shown in preferred form, an upright frame comprising a horizontally disposed base or foot piece 1 provided with 50 rigid vertical end standards or posts 2, is mounted in a suitable case or cabinet 3 upon

a slide 4 to be moved bodily toward the front or open side of the cabinet which is closed by suitable doors, and is pivotally mounted, as at 5, to rotate bodily upon said pivot. A 55 pair of transverse end bars 6 and 7 are rigidly secured upon the upper ends of the posts 2 and the extremities of these bars are connected by side rails 8 and 9 constituting parallel hanger supports on which the usual 60 coat forms 10 may be readily supported. Presser members 11 and 12 in the form of depending loops are rigidly secured to the under side of the bars 6 and 7 respectively 65 and prevent garments at the ends of the rails 8 and 9 from pressing against the ends of the cabinet.

70 Preferably the several parts are of tubular construction, but more particularly the side rails 8 and 9, and these rails are each 75 formed with downturned end portions which are journaled in sockets 13 formed on the ends of the end bars 6 and 7. Each rail is split or divided intermediate its ends into two like parts, being preferably severed obliquely 80 to provide angular abutting ends 14, and a latch which will permit of the sliding of the hangers over the closed joint without trouble, is inclosed within the end of one part of each rod to engage the other part. This 85 latch may be in the form of a spring projected bolt 15 having a handle 16 extending through a slot 17 in the under side of the part of the rail in which the bolt is inserted, whereby it may be retracted against the ac- 90 tion of the spring 18, a stop 19 anchoring the inner end of the spring, and the outer end portion of the bolt being tapered as indicated at 20 to readily enter the opposed end of the other part of the rail. 95

In operation, as clearly indicated in Fig. 5, when the frame is drawn bodily to the front of the cabinet, the hanger rail 8, for example, may be unlatched and its two sections swung outwardly, pivoting in the 100 sockets 13, as indicated, so that both sides of the garments on the hangers carried by this rail are free for inspection, dusting and the like. When the parts are swung into alignment and connected by the latch or bolt, 105 they become a rigid continuous member upon which the hangers may be slid from end to end without interference from the joint connecting the parts. By turning the frame on its pivot 5, the companion rail 9 110 may be brought to the front and because of its pivoted two part construction, may like-

wise be swung outwardly so that all parts of the garments which are hung therefrom become easily accessible without removing the hangers on which they are placed or removing the same one by one from the supporting rail. Thus a great deal of time and labor is saved without in any way affecting the rigidity or operation of the structure for ordinary display purposes, while the advantages of the construction over the old type are very great.

Obviously, changes in the details of construction may be made without departing from the spirit of my invention and I do not care to limit myself to any particular form or arrangement of parts.

What I claim is:—

The combination of a cabinet having a base piece rotatable and bodily shiftable therein with an upright end post rigidly secured on each end of the base, a transverse

end bar rigidly supported between its ends on the upper end of each post, upright sockets on the extremities of the end bars, and side rails connecting corresponding extremities of the end bars, each formed of a pair of tubular sections, one end of each being downturned and journaled in the socket of the end bar, whereby the section may be turned into alignment with the end bar, the free ends of the sections being detachably connectible in a flush joint to form a continuous side rail having a smooth unbroken exterior when they are turned into alignment with each other.

In testimony whereof I affix my signature in the presence of two witnesses.

GEORGE F. COOPER.
